CLAIM

The ornamental design for cover plate for a data logger, as shown and described.

DESCRIPTION

FIG. 1 is a perspective view of a cover plate for a data logger showing our new design;

FIG. 2 is a frontal view of the cover plate for a data logger shown in FIG. 1;

FIG. 3 is a rear view of the cover plate for a data logger shown in FIG. 1;

FIG. 4 is a side view thereof as viewed from the left-hand side of the cover plate for a data logger shown in FIG. 1;

FIG. 5 is a side view thereof as viewed from the right-hand side of the cover plate for a data logger shown in FIG. 1;

FIG. 6 is a top view thereof; and,

FIG. 7 is a bottom view thereof.

The broken lines shown in the drawings illustrate portions of the cover plate for a data logger that form no part of the claimed design.
